INSTRUMENT CONTROL

Louis Spraggen, Bridgeport, Conn., assignor to
 Automatic Locking Devices, Incorporated,
 Bridgeport, Conn., a corporation of Connecticut

Application May 18, 1944, Serial No. 536,126

8 Claims. (Cl. 192—8)

1

This invention relates to control instruments having rotatable shaft operating means, and more particularly to an instrument of this type having integral locking means associated with its operating shaft.

In electrical, radio, and other equipment, instruments operated by rotatable shafts are in general use. When these instruments are subjected to vibration, jarring, rough handling and the like, or when the control means for the instruments are inadvertently struck a blow, the adjusted settings are often disturbed, and this is particularly true if the shafts are unbalanced, as in the case of variable condensers having rotary plate assemblies statically unbalanced, or where shafts are under constant torque due to spring action.

An object of the invention is to provide a control instrument having integral automatic locking means associated with the operating shaft, so that accidental disturbance of the instrument setting is prevented, said means being so constructed that the instrument may be operated solely by the usual operating movements heretofore employed with instruments of this type, the shaft being unlocked at the initiation of the operating movement, and automatically locked at the termination of such movement.

Another object of the invention is to provide a control instrument having in-built automatic locking means of this character arranged in such manner that the usual mounting means for the various types of instruments, and the usual operable means for turning the shaft, may be employed substantially without alteration or relocation.

These objects are accomplished by the provision of a novel automatic locking mechanism having a sleeve mounted on and anchored to the frame of the instrument for encircling the operating shaft thereof to function as a bearing for same, the mechanism having an operable member located as an extension of the instrument shaft, and having means associated with the operable member, sleeve and shaft for unlocking, turning and automatically locking the latter in response to an operator moving and then releasing the operable member. This locking means guards against unintentional movement of the shaft in either direction, and comprises a pair of opposed single-direction automatic locks, each preventing movement of the shaft in a direction opposite to that prevented by the other.

The locking mechanism of this invention is extremely compact, and may be made compara-

2

tively small in size, so that it has the outward appearance of a collar on a shaft, occupying approximately an equivalent space, yet it is positive in operation, locking the shaft and instrumentalities controlled thereby against all accidental or casual movement.

Due to the compactness of the operating and locking means, and small space required, instruments made according to this invention may be used where it is desired to have the operable part flush with the instrument panel, this part, for instance, being in the form of a slotted head for receiving a screw driver or the like. This arrangement may be employed where only infrequent adjustments are required, for instance in trimming condensers and has the advantage that the likelihood of the adjustment being tampered with is minimized, and the danger of the operable part being struck by a moving object eliminated.

Other features and advantages will herein-after appear.

In the accompanying drawings, which show the device of the present invention on approximately a 2 to 1 scale:

26. Figure 1 is a fragmentary front elevation of a panel supporting an instrument made according to the invention.

Fig. 2 is a vertical section taken on the line 2—2 of Fig. 1.

30. Fig. 3 is a rear elevation of the instrument mounted on the panel.

Fig. 4 is an enlarged axial section taken through the operating and locking mechanism for the instrument.

35. Fig. 5 is a section taken on the line 5—5 of Fig. 4.

Fig. 6 is a section taken on the line 6—6 of Fig. 4, and

Fig. 7 is an exploded view of the operating and locking assembly of the invention.

The embodiment of the invention illustrated herein, referring particularly to Figs. 1 through 3, comprises a variable condenser, designated generally by the numeral 10. The condenser 10 has 45 a supporting frame or body 11 on which is mounted a stationary plate assembly 12 and a rotary plate assembly 13, the latter being carried by an operating shaft 14 which extends through the supporting body 11.

50. For the purpose of mounting the condenser 10 on a panel 15, the body 11, which may be of insulating material, has a pair of bored and threaded bosses 16, which extend through apertures therein, the ends 17 of the bosses being laid over at the 55 rear of the body as shown in Fig. 2.

According to the present invention, the condenser assembly 10 has an operating and locking mechanism integrally affixed to the end plate 11 for controlling the shaft 14, and therefore the movable plate assembly 13 of the instrument, which, as shown in Fig. 3, is carried by the shaft in the usual manner, resulting in an unbalance of the latter. This mechanism functions in such a manner that the standard operating movements for changing the rotative position of the plate assembly 13 may be employed without any additional motions whatsoever being required, yet the plate assembly is positively locked in any position to which it may be adjusted, regardless of jarring, vibration, and the like. Thus a simple turning movement may be employed to operate the condenser, the lock of the mechanism being automatically made inoperative at the initiation of the turning movement, and automatically becoming operative again at the termination of such movement.

This locking and operating mechanism, being extremely compact, may be made to occupy very little space at the front of the supporting body 11. Therefore, the mounting bosses 16 for the condenser need not be altered or relocated in any manner, nor is it necessary to relocate or substantially alter the exterior of the operable member for the condenser which may extend through the panel 15.

Accordingly, as shown in Fig. 4, the body 11 at the point where the shaft 14 passes through it, is adapted to mount a sleeve 18 which may encompass the shaft and function as a bearing for same. The sleeve 18 is rigidly fastened to the body against turning, and for this purpose has a shoulder 18a which engages the front face 11a of the body, the end 18b of the sleeve at the rear of the body being laid over to securely hold it in place, and against turning.

As seen in Fig. 7, the other end of the sleeve 18 is of larger diameter and bore to provide a locking drum 18c the bore 18d of which is cylindrical and concentric with the axis of the shaft 14.

The end of this shaft extends partially through the drum 18c and carries a press-fitted ring 19, one side of which abuts the internal shoulder 18e of the sleeve, the ring being held against this shoulder by a spring spider 14a engaging the rear of the body 11 and a shoulder 14b on the shaft, so that the rotary plate assembly 13 is axially centralized in the stationary plate assembly 12.

The drum 18c and ring 19 are adapted to cooperate with each other to lock the shaft 14 against turning with respect to the body 11, and for this purpose, see Fig. 7, the periphery 19a of the ring, which is cylindrical, has a plurality of reliefs each of which constitutes a pair of opposed wedging surfaces 19b and 19c.

When the ring is in place on the shaft 14 and within the drum 18c, as in Figs. 4 and 5, the cylindrical surfaces 19a of the ring are equispaced from the bore 18d of the drum and therefore concentric therewith, while the wedging surfaces 19b and 19c of each pair are spaced from the bore 18d, but incline so that they approach the latter.

As seen in Fig. 5, a plurality of pairs of locking rollers 20 and 21 are located between the wedging surfaces 19b and 19c of the ring, and the bore 18d of the drum, each pair being yieldably held separated and in wedging position against their respective surfaces by helical compression springs 22. The rollers 20 prevent counterclockwise turning of the ring 19 and shaft 14 with respect to the drum 18c, as viewed in Fig. 5, and the rollers

21 clockwise turning, and therefore the shaft and rotary plate assembly 13 are locked to the body 11 against turning in each direction.

For the purpose of releasing the shaft 14, and for turning same to vary the condenser, an operable member in the form of a disk 23 is rotatably mounted in the bore 18d of the drum 18c. The disk 23 has a plurality of equispaced lugs 23a extending from its periphery into the space between the cylindrical surfaces 19a of the ring and the bore 18d of the drum, the lugs being adapted to engage and dislodge from wedging position either the rollers 20 or the rollers 21, according to whether the disk 23 is turned in one direction or the other respectively.

Force may be applied to the disk 23 to turn same for unlocking the rollers through the provision of any suitable means. However, the device of this invention, due to its compactness and small size, is particularly suited to permit operation of the disk 23 by means of a central slotted boss 24 integral with the disk as shown in Fig. 4, the boss being flush with the instrument panel 15 and adapted to be operated through the use of a screw driver.

The use of a non-projecting or flush type operable member in connection with the condenser 10 requires only a slight spacing of the latter from the panel, as indicated by the spacing sleeves 30 16a, and therefore but a small amount of additional room is taken. Such slotted operable member and flush mounting may be used where but infrequent adjustment of the instrument is required, and has the advantage of minimizing tampering, and eliminating breakage where moving objects might pass by the panel.

According to the invention, after unlocking of either one or the other of the sets of rollers 20, 21 in response to turning of the disk 23, so that the shaft 14 is unlocked, means are provided so that a continuation of this turning will drive the shaft with it and vary the capacity of the condenser 10. This may be accomplished by the provision of a lost-motion driving connection between the disk and shaft, such a connection being shown in Figs. 4 through 7. This connection comprises a pin 25 press-fitted in the ring 19 and extending into an aperture 26 in the disk 23, the aperture being larger in diameter than the pin so that a loose fit results between same.

The pin 25 and aperture 26 are so located with respect to the lugs 23a that the pin is centralized in the aperture when the lugs are halfway between the rollers 20 and 21 so as not to engage same, as in Fig. 5.

Retention of the disk 23 in the drum 18c is accomplished by a cylindrical ring 27 press-fitted over the drum, having an inwardly extending flange 27a engaging the outer side of the disk to permit turning but not removal thereof.

Normally, as shown in Fig. 5, when no turning force is being applied to the disk 23, the springs 22 hold the rollers 20, 21 in wedging position so that the shaft 14 is locked to the body 11. For this condition the capacity of the condenser will be maintained invariable, regardless of moderate vibration, shock, etc., to the instrument. If it is desired to adjust or vary the capacity of the condenser, turning force is applied, as by a screw driver, to the disk 23. As the latter turns, it will first take up the clearance between the pin 25 and aperture 26, without moving the shaft 14, this initial action however permitting the lugs 23a to dislodge one or the other of the sets of rollers 20, 21 from their wedging positions, depending

on the direction of turning. This unlocks the shaft, and continued turning of the disk will now drive the shaft to any new position desired. During this movement the set of rollers not dislodged will not cause interference because each set prevents movement in one direction only. Upon removal of the turning force from the disk 23 the springs 22 will immediately again move the dislodged rollers to wedging position to lock the shaft 14 in its new adjustment, this movement also re-turning the disk to intermediate position with respect to the rollers and shaft, as permitted by the lost motion connection to the latter.

As shown in Figs. 4 and 5, the ring 19 may be keyed to the shaft 14 by a pin 28 to securely position the ring.

Variations and modifications may be made within the scope of this invention and portions of the improvements may be used without others.

I claim:

1. The combination of a panel; a frame mounted on the panel; means carried by the frame for varying a condition, including a shaft rotatable with respect to the frame; means carried by the frame and located between the panel and the frame for automatically wedgingly locking the shaft to the latter; an operable member rotatably mounted with respect to the frame and panel, extending through the latter and having a face substantially flush with the front of the panel, said face having a groove to receive the tip of a screw driver for operation thereby; and means for rendering inoperative said locking means, and for turning the shaft in response to turning of the operable member by an applied force, the locking means automatically becoming again operative upon removal of said applied force from the operable member.

2. A control instrument comprising means for varying a condition; a frame and an operating shaft extending therethrough; a sleeve fastened to the frame, encompassing the shaft; a ring attached to the shaft adjacent its end, engaging the end of the sleeve to prevent axial movement of the shaft in one direction; spring means engaging the frame and shaft to yieldably hold the said ring and sleeve in engagement; wedging means for automatically locking the ring to the sleeve to prevent turning of the shaft; an operable member mounted on the sleeve to be rotatable in the same directions as the shaft; and means for rendering said locking means inoperative and for turning the shaft in response to turning of the operable member as a result of the application of force thereto, the locking means automatically becoming again operative upon removal of said force from the operable member.

3. A control instrument comprising means for varying a condition, including an operating shaft; a frame for supporting said means; a sleeve fixed to the frame, receiving the shaft and rotatably supporting same; a locking drum rigid on the sleeve, having an internal cylindrical surface spaced from the shaft; a ring rigidly secured to the shaft and located inside the locking drum, having a wedging surface spaced from and inclined to the cylindrical surface of the drum; a wedging roller; and means for yieldably holding same in wedging engagement with the surfaces of the drum and ring to prevent turning of the latter and the shaft; an operable member rotatably mounted in the drum, having a lug extending between the surfaces of the drum and ring for engagement with the wedging roller, and having a lost-motion driving connection with the

shaft so that when force is applied to cause turning of the member in one direction it will first move the wedging roller out of wedging position to unlock the ring and shaft from the drum, and then drive the shaft as the turning is continued, the roller being automatically moved to wedging position again by said yielding means to lock the shaft upon removal of the turning force from the operable member.

10. A control instrument comprising means for varying a condition, including an operating shaft; a frame for supporting said means; a sleeve fixed to the frame, receiving the shaft and rotatably supporting same; a locking drum rigid on the sleeve, having an internal cylindrical surface spaced from the shaft; a ring rigidly secured to the shaft and located inside the locking drum, having a wedging surface spaced from and inclined to the cylindrical surface of the drum; a wedging roller, and means for yieldably holding same in wedging engagement with the surfaces of the drum and ring to prevent turning of the latter and the shaft; and an operable member rotatably mounted in the drum, having a lug extending between the surfaces of the drum and ring for engagement with the wedging roller, and having a recess adjacent the side surface of the ring, the latter having a fixed pin extending into the said recess with a loose fit, adapted to engage the walls thereof so that when force is applied to cause turning of the operable member it will first move the wedging roller out of wedging position to unlock the ring and shaft from the drum, and then drive the shaft as the turning is continued, the roller being automatically moved to wedging position again by said yielding means to lock the shaft upon removal of the turning force from the operable member.

5. A control instrument comprising means for varying a condition; a two-part operating structure for said means consisting of a frame and a shaft, one part carrying a mass having a center of gravity noncoincidental with its axis whereby unbalance occurs, and the other part being adapted for mounting on a base member; a bearing sleeve connected to the frame and mounting said shaft for rotation with respect to said frame; a flange carried by the sleeve; a collar permanently fastened to the flange and encompassing the shaft in spaced relation thereto; wedging means disposed in the space between the shaft and collar for automatically locking the shaft to the collar; an operable member rotatably mounted in the collar for movement with respect to the shaft and collar; and means for rendering said wedging means inoperative and for turning the shaft with respect to the frame in response to turning of the operable member by an applied force, the wedging means automatically becoming again operative upon removal of said applied force from the operable member.

6. A control instrument comprising means for varying a condition; a two-part operating structure for said means consisting of a frame and a shaft, one part carrying a mass having a center of gravity noncoincidental with its axis whereby unbalance occurs, and the other part being adapted for mounting on a base member; a bearing sleeve having one end connected to the frame and mounting said shaft for rotation with respect to said frame; a flange carried by the other end of the sleeve; a collar permanently fastened to the flange and encompassing the shaft in spaced relation thereto; wedging rollers disposed in the space between the shaft and collar for

automatically locking the shaft to the collar; an operable member rotatably mounted in the collar for movement with respect to the shaft and collar; and means for rendering said wedging rollers inoperative and for turning the shaft with respect to the frame in response to turning of the operable member by an applied force, the wedging rollers automatically becoming again operative upon removal of said applied force from the operable member.

7. A control instrument comprising means for varying a condition; a two-part operating structure for said means consisting of a frame and a shaft, one part carrying a mass having a center of gravity noncoincidental with its axis whereby unbalance occurs, and the other part being adapted for mounting on a base member; a bearing sleeve having one end connected to the frame and mounting said shaft for rotation with respect to said frame, said sleeve projecting from the frame and having a flange at the outer end; a collar having one edge fastened to the flange, said collar encompassing the shaft in spaced relation thereto; wedging rollers disposed in the space between the shaft and collar for automatically locking the shaft to the collar; an operable member rotatably mounted within the collar for movement with respect to the shaft; means for closing the outer end of the collar to enclose said wedging rollers in said space; and means for rendering said wedging rollers inoperative and for turning the shaft with respect to the frame in response to turning of the operable member by an applied force, the wedging rollers automatically becoming again operative upon removal of said applied force from the operable member.

8. A control instrument comprising means for varying a condition; a two-part operating structure for said means consisting of a frame and a shaft, one part carrying a mass having a center of gravity noncoincidental with its axis whereby unbalance occurs, and the other part being adapted for mounting on a base member; a bearing sleeve clamped at one end to the frame and mounting said shaft for rotation with respect to said frame; an enlarged flange carried by the

other end of the sleeve, said flange being recessed to form a cylindrical surface encompassing the shaft in spaced relation thereto; wedging rollers disposed in the space between the shaft and 5 cylindrical surface for automatically locking the shaft to the sleeve; an operable member rotatably mounted within the recess for movement with respect to the shaft and sleeve; and means for rendering said wedging rollers inoperative 10 and for turning the shaft with respect to the frame in response to turning of the operable member by an applied force, the wedging rollers automatically becoming again operative upon removal of said applied force from the operable member.
